United States Patent Office.

MILTON DAY, OF BALTIMORE, MARYLAND.

Letters Patent No. 79,961, dated July 14, 1868.

IMPROVEMENT IN CORN-SHELLERS.

The Schedule referred to in these Letters Patent and making part of the same.

TO ALL WHOM IT MAY CONCERN:

Be it known that I, MILTON DAY, of Baltimore city, county of Baltimore, and State of Maryland, have invented certain new and useful Improvements in Corn-Shellers; and I do hereby declare that the following is a full, clear, and exact description of the same, reference being had to the accompanying drawing, and the letters of reference marked thereon, making part of this specification, in which—

Figure 1 is a front view of the corn-sheller, with half of the case removed.

Figure 2 is a rear view of the corn-sheller without the case.

Figure 3 is an edge view, partly in section, showing the cogs on the rim, for a spur-gearing.

Figure 4 is a sketch of one of the palms.

The nature of my invention consists in constructing a corn-sheller with two palms, each provided with two, three, or more fingers or tines. These palms are provided at each end with slots, which work upon shanks extending entirely across the inside of the corn-sheller, and which are fastened to the rim by any convenient means. Upon these shanks are arranged spiral springs, extending from the rim to the slotted ends of the palms, which springs cause the palms to either give or collapse, according to the size of the ear of corn to be shelled. On the outside of the rim there is arranged a series of cogs, either square across or bevelled, to work into the driving-gear wheel, of any construction, which may be worked by hand, as with a common crank and handle, or any other convenient way.

To enable others skilled in the arts to make and use my invention, I will now proceed to describe its construction and operation.

A is the box or casing, enclosing the rim and palms; B B are the palms; C C, the springs; D, the main driving-wheel; E, the cogs on the rim, either spur or bevelled.

b b are the tines or fingers. d d are the shanks, extending across the inside of the corn-sheller, upon which are arranged the springs C C. d' d' are the slots or holes in each end of the palms B B, through which pass the shanks d d. e e are grooves in the casing, by which the machine can be fitted to a corresponding dove-tail piece, fastened to any framing, box, or other suitable place. F is the circular centre-piece or ring, to the flange of which the case A is fastened by means of the rivets f f.

This sheller may be used horizontally, as shown in figs. 1 and 2, or vertically, as shown in fig. 3, in which case the cog-wheel is entirely encased, except at its outer edge, which is left open, in order to receive motion direct from the driving-wheel, in which case the latter works in independent bearings outside of the shelling-mechanism.

The double case is an exact counterpart of the single case, as shown in fig. 1.

If used as in figs. 1 and 2, then the ears can be placed into the sheller, and the corn and ears will drop through together; but if vertically, the ears must be fed in by the hand, which may be from either side, and, the proper motion being given to the driving-wheel, the ears will be drawn in, and the corn will drop through an opening in the case below, and the ears will fall out to one side.

I am aware that palms operated by springs have been used before, but in devices that differ from the one shown, and which fail to possess that degree of practical utility which constitutes its chief recommendation.

Having thus fully described my invention, what I claim therein as new, and desire to secure by Letters Patent of the United States, is—

The combination, in a corn-sheller, of two palms, B B, each having three or more fingers or tines, b b, to embrace the cob, with the springs C C and shanks d d, when the latter are permanently secured to the rim, all constructed and arranged substantially as described, and for the purpose specified.

In testimony whereof, I have signed my name to this specification in the presence of two subscribing witnesses.

MILTON DAY.
